UNITED STATES PATENT OFFICE.

GEORGE G. BAYNE, OF BUSHNELL, ILLINOIS.

ROAD DRAG.

1,417,882.

Specification of Letters Patent. Patented May 30, 1922.

Application filed January 12, 1920. Serial No. 350,958.

To all whom it may concern:

Be it known that I, GEORGE G. BAYNE, a citizen of the United States, and a resident of the city of Bushnell, in the county of Mc-
5 Donough and State of Illinois, have invented certain new and useful Improvements in Road Drags; and I do hereby declare that the following is a full, clear, and exact description of the same, reference being had
10 to the accompanying drawings, and to the numerals of reference marked thereon, which form a part of this specification.

This invention relates to implements for dragging, smoothing, grading and surfac-
15 ing roads.

One of the principal objects of the invention is to provide improved means for connecting such implements to the hauling means such as a team of horses or tractor.
20 Another object of the invention is to provide improved means for adjusting the angular position of the drag relative to the hauling means.

A further object of the invention is to pro-
25 vide improved means for adjusting the angular position of the longitudinal and transverse members of the drag.

Other and further important objects of this invention will be apparent from the dis-
30 closures in the drawings and specification.

The invention (in a preferred form) is illustrated in the drawings and hereinafter more fully described.

On the drawings:

35 Figure 1 is a plan view of a drag constructed in accordance with the present invention.

Figure 2 is a side view of the same.

Figure 3 is a section on the line 3—3 of
40 Figure 4.

Figure 4 is a section on the line 4—4 of Figure 3.

Figures 5 and 6 are plan views of the drag in two positions of adjustment.

45 As shown in the drawings:

The drag comprises a front plane 1, a rear plane 2, deck boards 3, and longitudinal connecting boards 4 pivotally connected to the front and rear planes and deck boards by
50 pins 5. The front plane consists of a sheet of steel having pairs of vertical angle bars 6 secured to its rear face. Between the lower end of each pair is pivotally secured the end of a block 7 pivotally secured to one of the longitudinal members 4 by one of the pins 5.

This double connection allows the angle of the front plane to be adjusted vertically as well as horizontally with respect to the members 4.

For adjusting the angle of the front plane in a vertical direction a notched segment 8 is attached to the front deck board 3. To the center of this segment a lever 9 is pivoted having a latch 10 adapted to engage one or other of the notches in the segment 8. A supplementary lever 11 mounted on the lever 9 is provided for retracting this latch against the action of its spring when desired. A link 12 connects this lever to the angle bars 6 so that the angle of the front plane may be adjusted by moving the lever 9 to and fro.

The angular position of the planes and deck boards with respect to the longitudinal members 4 is adjusted by means of a rearwardly projecting arm 13 secured to the front plane and braced laterally by angle bars 14. The arm 13 passes beneath an angle bar 15 supported at each end by blocks 16 secured to the center deck board as shown more particularly in Figure 4. In the upper edge of this angle bar 15 are formed a series of notches 17 adapted to be engaged by a latch 18 pivotally secured to a bracket 19 projecting upwardly from the arm 13. At its free end the latch is arranged to drop between two projections 20 on the arm 13, between which it is releasably secured by a bolt 21.

The drag is attached to the hauling means by a pair of chains 22, connected at their front ends by a ring 23 and passing rearwardly through guide rings 24 secured to the members 4. To the rear ends of these chains are attached links 25 secured to a bracket 26 on a central longitudinal member 27. This member 27 is pivotally connected to the front and rear planes and deck boards in a similar manner to the side members 4. The rear end of the member 27 is formed into a handle 28, by which the movement of the drag may be guided.

The operation of the device is as follows:

The angle of the front plane is adjusted by means of the lever 9 to suit particular requirements. When working roads or grounds which are moist and wet, better results will be attained by inclining the lower edge of the front plane rearwardly so that it also acts as a drag, but when working very dry soils the front blade is preferably in-

clined in the opposite direction. It will be evident that the device is equally as well adapted for field as road work.

The next step is to adjust the angle of the front plane horizontally so as to throw the soil or rocks in the desired direction. This is accomplished by the latch 18. By providing such adjusting means it is possible to throw the earth in the same direction irrespective of the direction of movement of the drag. Thus in filling a ditch the drag may be drawn therealong to one end, swung around and then drawn back after reversing the angular position of the front plane.

I am aware that numerous details of construction may be varied through a wide range without departing from the principles of this invention, and I therefore do not purpose limiting the patent granted otherwise than necessitated by the prior art.

I claim as my invention:

1. In a drag, a front plane, deck members, a rear plane and longitudinal members pivotally connected to the front and rear planes and deck members, a pair of chains, a ring connecting the front ends of the chains together, means for connecting the rear ends of the chains to a point adjacent the midpoint of the rear plane, and guide rings for the chains secured to said longitudinal members.

2. In a drag, a front plane, deck members, a rear plane and longitudinal members pivotally connected to the front and rear planes and deck members, hauling chains in the form of a quadrilateral, said chains being attached to the rear of the drag at its middle portion, and means for varying the angular relation of the members without varying the relative position of said attachment of the hauling chains.

3. In a drag, a front plane, transverse deck members, a rear plane and longitudinal members pivotally connected to the front and rear planes and deck members, a bracket fixed to one of the transverse members, a rack fixed to another of the transverse members, and a latch secured to the bracket adapted to engage one or other part of said rack whereby the angular relationship between the longitudinal and transverse members may be adjusted as desired.

4. In a drag, the combination of a front and a rear plane, deck members connecting said planes, means for varying the angular relation between the planes and deck members, and hauling chains for the drag, said chains being attached to the said varying means.

5. In a drag, the combination of a front and a rear plane, deck members connecting said planes, means for adjusting the angular relation between said planes and deck members, and hauling chains for the drag, said chains being attached to the said adjusting means at the rear of the drag and passing through rings attached to the front of the drag.

6. In a road drag, a front plane, a rear plane, longitudinal members pivotally connected to said planes, means at the rear of the drag for varying the angular position of the planes, hauling chains for the drag, and flexible connections between said hauling chains and said varying means.

In testimony whereof I have hereunto subscribed my name in the presence of two subscribing witnesses.

GEORGE G. BAYNE.
